DRILL BIT

Clement M. Kucera and Robert G. Peter, Houston,
Tex., assignors to Reed Roller Bit Company,
Houston, Tex., a corporation of Texas

Application November 13, 1951, Serial No. 255,918

15 Claims. (Cl. 255—300)

1 This invention relates generally to drill bits, and particularly to roller bits for drilling deep wells in the earth.

The roller bits now in common use (for example, the so-called cross roller bit and the cone bit) embody a bit head in which rollers are rotatably mounted. The bit head is connected to the end of a drill stem which is rotated to cause the rollers to roll upon the bottom of the hole and thereby cut or crush the formation. A mud-laden drilling fluid is pumped downwardly through the drill stem and bit, and rises upwardly in the space between the drill stem and the wall of the hole to the surface of the earth. One of the most important desired functions of the drilling fluid thus circulating is quickly to remove the cut or crushed particles of the formation from the bottom of the hole and from the rollers and the adjacent walls of the head. This function is not always efficiently performed, because in various formations, particularly in sticky shales, the particles of the formation adhere to the rollers and accumulate between the rollers and the adjacent walls of the head, as a result of which the rollers either cease to rotate and are worn by skidding upon the bottom of the hole, or the abrasive particles of the formation wear away the rotating ends of the rollers, the adjacent stationary walls of the head, and the bearings of the rollers. This failure of the mud-laden drilling fluid to perform this desired function occurs in various types of roller bits, and particularly in those roller bits in which the mud-laden drilling fluid is discharged from the bit head upon the bottom of the hole.

This invention has for one of its general objects the provision of a new and improved roller bit through which the drilling fluid will freely circulate to perform the desired function of quickly removing the particles of formation from the bottom of the hole and from the head and the rollers.

The roller bits in common use are heavy and hard to handle, but it is necessary that they be handled by the men on the rig, particularly when they are screwed on or off the drill stem.

This invention has for another of its general objects to provide a new and improved roller bit which may be easily handled by the men on the rig and easily screwed on or off the drill stem.

Other objects will hereinafter appear.

The preferred embodiments of the invention are illustrated by the accompanying drawings in which Figs. 1 through 6 illustrate the invention embodied in a cross roller bit and Figs. 7

2 through 12 illustrate the invention embodied in a cone bit.

Figs. 1, 2 and 3 are perspective views of the cross roller bit;

Fig. 4 is a fragmentary view illustrating the drilling fluid discharge passageways;

Fig. 5 is a bottom plan view; and

Fig. 6 is a fragmentary view illustrating the drilling fluid exit passageway adjacent the upper outer portion of the side roller;

Figs. 7, 8 and 9 are perspective views of the cone bit;

Fig. 10 is a fragmentary view illustrating the drilling fluid discharge passageways;

Fig. 11 is a bottom plan view; and

Fig. 12 is a fragmentary view illustrating the drilling fluid exit passageway adjacent the upper outer portion of the cone.

Referring first to the cross roller bit shown in Figs. 1 through 6, the bit head is indicated at 1. It may be provided with the usual threaded shank 2 for attachment to the drill stem (not shown). The head 1 has a pair of oppositely disposed depending cross roller bearing extensions 3 and 4 on which are rotatably mounted the cross rollers 5 and 6. The head also has a pair of oppositely disposed depending side roller bearing extensions 7 and 8 on which are rotatably mounted the side rollers 9 and 10. The side rollers are rotatable on axes inclined downwardly and inwardly from the upwardly and inwardly inclined inner walls of the bearing extensions 7 and 8 so that the upper portion of the side rollers is at a substantial distance from the periphery of the head. The side rollers and cross rollers may be rotatable in the usual manner on suitable pins (not shown). The outer ends of the pins may be supported in the usual manner by the depending bearing extensions 3, 4, 7 and 8 and the inner ends may be connected by the usual bridge 11. The bearing extensions 7, 8, 9 and 10 of the head form a recess for the rollers.

Drilling fluid pumped downwardly through the drill stem (not shown) passes through the bore 12 of the threaded shank and thence through the nozzles 14 and 15 by which it is discharged downwardly toward the bottom of the hole.

One of the most important desired functions of the drilling fluid is to keep the rollers clean and to quickly remove from the bottom of the hole the particles of material cut or crushed by the rollers, and to convey these particles of the formation upwardly between the drill stem and the wall of the hole to the surface of the earth. This desired function has not always been per-

formed by the drilling fluid in the conventional cross roller bit because particles of the formation have been trapped between the side rollers 9 and 10 and their bearing extension 7 and 8, and these particles have accumulated in the head above the side rollers particularly when the bit has been used in sticky shales, as a result of which the side rollers have been prevented from rotating, or the abrasive particles of formation have worn the side rollers, the side roller bearing extensions and associated parts. To prevent this, this invention may be embodied in the conventional cross roller bit by providing special side roller bearing extensions 7 and 8. It will be noted that these extensions are provided with special drilling fluid exit passageways 16 and 17 which will now be described.

In the embodiment shown, the side roller bearing extension 8 with its drilling fluid exit passageway 17 is the same as the side roller bearing extension 7 with its drilling fluid exit passageway 16, and so a description of the latter will describe the former. The side roller 9 is rotatably supported by the lower portion of the side roller bearing extension 7 in the usual manner. The drilling fluid exit passageway 16 is located adjacent the upper outer portion of the side roller 9. The drilling fluid discharged downwardly toward the bottom of the hole by the drilling fluid discharge passageways 14 and 15 will quickly remove from the bottom of the hole the particles of formation cut or crushed by the rollers, and these particles will not accumulate within the head above the rollers because they will not be trapped therein but on the contrary will move with the drilling fluid outwardly through the drilling fluid exit openings 16 and 17 to be carried to the surface of the earth. In other words the drilling fluid will be permitted to thus circulate into the recess of the head above the rollers and thence from the interior to the exterior of the head through the exit openings 16 and 17 and thereby perform its important and desired function above referred to.

It will be noted that the side roller bearing extension 7 increases in thickness upwardly to the point at which the drilling fluid exit passageway is provided and that ample strength to support the side roller 9 is thus afforded. It will also be noted that the head 1 tapers inwardly and upwardly substantially at the point where the drilling fluid exit passageway 16 is provided so that the drilling fluid carrying the particles of the formation may move freely through the drilling fluid exit passageway 16 and thence upwardly in the ascending column of drilling fluid to the surface. It will also be noted that the drilling fluid will move out of the recess formed by the bearing extensions substantially axially of the side roller 9 through the drilling fluid exit passageway 16 so that the roller 9 will be kept clean and the particles of the formation will not accumulate in the recess defined by the bearing extensions.

The opening 16 is of such size and the walls of the opening are so rounded as to provide a convenient handle which may be grasped by the hand of the man on the rig who is handling the bit. This will make very heavy bits easy to handle. The openings 16 and 17 are oppositely disposed and if desired any suitable lever bar may be inserted through openings 16 and 17 to screw the threaded shank 2 of the bit into and out of the drill stem. This will render unnecessary the use of any special tools for connecting and dis-

connecting the threaded shank from the drill stem.

Referring now to Figs. 7 through 12 which illustrate the embodiment of the invention in a cone bit the bit head is indicated at 21. It may be provided with the usual threaded shank 22 for attachment to the drill stem (not shown). The head 21 has three depending bearing extensions 23, 24 and 25. Rotatably mounted on these extensions 23, 24 and 25 and rotatable on axes inclined downwardly and inwardly from the upwardly and inwardly inclined inner walls of said extensions are three substantially conical rollers 26, 27 and 28. These substantially conical rollers may be supported on the bearing extensions in the well-known manner by suitable pins. Drilling fluid pumped downwardly through the drill stem (not shown) passes through the bore 29 of the shank 22 and thence through the nozzles 30, 31 and 32 by which it is discharged downwardly toward the bottom of the hole. To cause the desired circulation of the drilling fluid from the recess of the head defined by the bearing extensions 23, 24 and 25 so that the rollers will be kept clean and the particles of the formation cut or crushed thereby will not accumulate in the recess, this invention is embodied in the bit described by providing a drilling fluid exit passageway in the head adjacent the upper outer portion of each of the rollers 26, 27 and 28. The drilling fluid exit passageway above the roller 26 is indicated at 33, the drilling fluid exit passageway above the roller 27 is indicated at 34 and the drilling fluid exit passageway above the roller 28 by the numeral 35. The drilling fluid discharged downwardly toward the bottom of the hole by the drilling fluid discharge passageways 30, 31 and 32 will circulate from the recess of the head formed by the bearing extensions outwardly through each of the drilling fluid exit passageways in a direction substantially in the plane of the axis of rotation of rollers adjacent thereto.

The openings 33, 34 and 35 and the walls thereof will form convenient handles for handling the bit, and a lever bar may be inserted therein for the purpose of screwing the shank 22 into and out of the drill stem.

It will be apparent from the foregoing that the invention will be found particularly useful in bits embodying rollers, depending lugs and tubes to discharge slush downwardly near the wall of the hole, because these elements substantially fill the bore of the hole.

The invention is not limited to the embodiments herein disclosed. Various changes, within the scope of the following claims, will occur to those skilled in the art.

We claim:

1. A cross roller bit having a head; said head having two oppositely disposed depending cross roller bearing extensions; and two oppositely disposed side roller bearing extensions; cross rollers mounted on the lower portions of said cross roller bearing extensions; side rollers mounted on the lower portions of said side roller bearing extensions and rotatable on axes inclined downwardly and inwardly from said side roller bearing extensions; said head having a drilling fluid discharge passageway to discharge drilling fluid toward the bottom of the hole; and each of said side roller bearing extensions having a drilling fluid exit passageway adjacent the upper outer portion of the side roller mounted thereon.
2. A cross roller bit having a head, cross rollers

and side rollers mounted on bearing extensions on the lower portion of said head, said head having a drilling fluid discharge passageway and drilling fluid exit passageways formed in certain of said extensions adjacent the upper outer portions of the rollers carried thereby.

3. A cone bit having a head, said head having three depending bearing extensions; and a substantially conical roller mounted on each of said extensions on an axis inclined downwardly and inwardly from said extensions, said head having a drilling fluid discharge passageway to discharge fluid toward the bottom of the hole, and each of said bearing extensions having a drilling fluid exit passageway adjacent the upper outer portion of the roller mounted thereon.

4. A cone bit having a head, and substantially conical rollers mounted on bearing extensions on the lower portion of said head, said head having a drilling fluid discharge passageway and drilling fluid exit passageways formed in certain of said extensions adjacent the upper outer portions of said rollers.

5. A roller bit having a head with a roller recess in the bottom thereof, one of the inner walls of said recess being inclined upwardly and inwardly toward the longitudinal axis of the head, and a roller mounted on said wall, said head having a drilling fluid exit opening through said wall above said roller, and a drilling fluid discharge passageway, whereby drilling fluid may flow into said recess above said roller and out of said recess through said exit opening.

6. A roller bit having a head with a roller recess in the bottom thereof, and a roller mounted in said recess, said head having a drilling fluid discharge passageway, and an exit opening through the wall of said recess adjacent the upper outer portion of said roller, whereby drilling fluid may flow into said recess above said roller and out of said recess substantially axially of said roller through said exit opening.

7. A roller bit having a head, said head having a recess in the bottom thereof, a roller cutter mounted on one of the walls of said recess to rotate adjacent said wall, and means to discharge drilling fluid downwardly toward the bottom of the hole, said head having a drilling fluid exit passageway adjacent the upper outer portion of said cutter and communicating with said recess and the space between the head and the wall of the hole so that drilling fluid laden with cuttings will flow from said recess through said passageway into said space.

8. A roller bit having a head, said head having a recess in the bottom thereof defined in part by an upwardly and inwardly inclined wall, a roller cutter mounted on said wall in said recess to rotate adjacent said wall on an axis inclined downwardly and inwardly, and means to discharge drilling fluid downwardly toward the bottom of the hole, said head having a drilling fluid exit passageway adjacent the upper outer portion of said cutter and communicating with said recess and the space between the head and the wall of the hole so that drilling fluid laden with cuttings will flow from said recess through said passageway into said space.

9. A roller bit having a head, said head having a recess in the bottom thereof, a plurality of rotatable cutters mounted in said recess, said recess being defined in part by an upwardly and inwardly inclined wall, at least one of said cutters being mounted on said wall in said recess to rotate adjacent said wall on an axis inclined

downwardly and inwardly, and means to discharge drilling fluid downwardly toward the bottom of the hole, said head having a drilling fluid exit passageway adjacent the upper outer portion of said cutter and communicating with said recess and the space between the head and the wall of the hole so that drilling fluid laden with cuttings will flow from said recess through said passageway into said space.

10. A cone bit having a head, said head having a recess in the bottom thereof, a plurality of substantially conical cutters mounted in said recess, said recess being defined in part by upwardly and inwardly inclined walls, each of said cutters being mounted on one of said walls in said recess to rotate adjacent said wall on an axis inclined downwardly and inwardly, and means to discharge drilling fluid downwardly toward the bottom of the hole, said head having a drilling fluid exit passageway adjacent the upper outer portion of each of said cutters and communicating with said recess and the space between the head and the wall of the hole so that drilling fluid laden with cuttings will flow from said recess through said passageways into said space.

11. A cone bit having a head, said head having a recess in the bottom thereof, a plurality of substantially conical cutters mounted in said recess, said recess being defined in part by upwardly and inwardly inclined walls, each of said cutters being mounted on one of said walls in said recess to rotate adjacent said wall on an axis inclined downwardly and inwardly, and means to discharge drilling fluid downwardly toward the bottom of the hole, said head having a drilling fluid exit passageway adjacent the upper outer portion of at least one of said cutters and communicating with said recess and the space between the head and the wall of the hole so that drilling fluid laden with cuttings will flow from said recess through said passageway into said space.

12. A cross roller bit having a head, said head having a recess in the bottom thereof, cross roller cutters and side roller cutters mounted in said recess, said recess being defined in part by upwardly and inwardly inclined walls, said side roller cutters being mounted on said walls in said recess to rotate adjacent said walls on axes inclined downwardly and inwardly, and means to discharge drilling fluid downwardly toward the bottom of the hole, said head having a drilling fluid exit passageway adjacent the upper outer portion of each of said side roller cutters and communicating with said recess and the space between the head and the wall of the hole so that drilling fluid laden with cuttings will flow from said recess through said passageways into said space.

13. A cross roller bit having a head, said head having a recess in the bottom thereof, cross roller cutters and side roller cutters mounted in said recess, said recess being defined in part by upwardly and inwardly inclined walls, said side roller cutters being mounted on said walls in said recess to rotate adjacent said walls on axes inclined downwardly and inwardly, and means to discharge drilling fluid downwardly toward the bottom of the hole, said head having a drilling fluid exit passageway adjacent the upper outer portion of at least one of said side roller cutters and communicating with said recess and the space between the head and the wall of the hole so that drilling fluid laden with cuttings will flow from

said recess through said passageway into said space.

14. A cross roller bit having a head, said head having a recess in the bottom thereof, cross roller cutters and side roller cutters mounted in said recess, means to discharge drilling fluid downwardly toward the bottom of the hole, said head having a drilling fluid exit passageway adjacent the upper outer portion of at least one of said roller cutters and communicating with said recess and the space between the head and the wall of the hole so that drilling fluid laden with cuttings will flow from said recess through said passageway into said space.

15. A roller bit having a head, said head having a recess in the lower portion thereof, a plurality of roller cutters mounted in said recess, means to discharge drilling fluid downwardly toward the

5

bottom of the hole, the said head having a drilling fluid passageway adjacent the upper outer portion of at least one of the said roller cutters and communicating with the said recess and the space between the said head and the wall of the hole so that drilling fluid and cuttings may circulate through the said passageway.
